UNITED STATES PATENT OFFICE.

JOHANN KÜBLER, OF BADEN, SWITZERLAND, ASSIGNOR TO AKTIENGESELLSCHAFT BROWN, BOVERI & CIE., OF BADEN, SWITZERLAND.

ANODE FOR MERCURY-VAPOR RECTIFIERS.

Application filed June 6, 1921, Serial No. 475,483, and in Switzerland June 18, 1920.

In the known cylindrical or hollow cylindrical forms of anodes for mercury-vapor rectifiers, it has been observed that the point whence the electric arc emanates, creeps upwards, that is to say towards the inlet insulator of the anode. This is due to the fact that the electric arc has a smaller ohmic resistance than the iron anode, and by reason of a lengthening of the light arc in combination with an equal shortening of the metallic path for the current through the anode material, there is produced automatically a diminution of the total resistance of the direct current circuit.

According to this invention the creeping of the point of emanation of the electric arc is obviated by constructing the anode in such a manner that the rising of the point of emanation of the electric arc will produce an increase in the total resistance of the direct current circuit. Namely, whereas hitherto the connection of the anode to the supply circuit has been situated approximately at its highest point, now according to this invention the current is supplied to it approximately at its lowest point, that is to say at its point situated nearest the cathode.

An example of a rectifier anode construction according to the invention is illustrated in the accompanying drawing, which represents a section of part of a rectifier with an inserted anode. In the drawing the anode is formed as a thin hollow cylinder *a* of iron which is closed at its lower end and has at the lowest point of its interior a thickened portion *c*. The current supply rod *b* is screwed into this thickened portion.

For the purpose of keeping the ohmic resistance of the path of the current through the centre of the anode as small as possible compared with the ohmic resistance of the path through the anode casing *a*, the supply rod *b* is made of generous dimensions and is composed of good conducting material, for instance, copper.

The annular cavity *d* between the anode casing *a* and the supply rod *b* may be utilized for the cooling of the anode, and is traversed by or filled with a cooling medium which must, of course, be a bad conductor of electricity. In the drawing air is the cooling medium, and its circulation is assisted by convection. In many cases however, the good conduction of heat through the thick copper rod *b* will suffice.

The entire anode is surrounded by the insulator *f* at the point where it passes through the wall *e* of the rectifier vessel. The rod *b* and anode *a*, *c*, may of course be made in one piece. Other forms of anodes besides those shown in the drawing can be readily designed.

What I claim is:—

1. An anode for a mercury vapor rectifier comprising a hollow cylinder closed at the end nearest the cathode and means for connecting a conductor directly to the closed end.

2. An anode for a mercury vapor rectifier and a conductor for connecting same to a supply circuit characterized by the feature that the anode is formed as a hollow cylinder closed at the end nearest the cathode, with a conducting stub rising in the interior of the cylinder from said closed end and that the said conductor is connected mechanically and electrically to said stub.

3. In the anode as defined in claim 1, means for introducing an insulating cooling medium between the interior of said hollow cylinder and said conductor.

4. A combination as claimed in claim 2 with the additional feature that the said conductor is screwed directly into the said stub.

In testimony whereof I have signed my name to this specification.

JOHANN KÜBLER.
